UNITED STATES PATENT OFFICE.

FRANK K. HESSE, OF BOSTON, MASSACHUSETTS, ASSIGNOR TO CODMAN & SHURTLEFF, OF SAME PLACE.

DESIGN FOR A TOE-CLIP FOR BICYCLES.

SPECIFICATION forming part of Design No. 26,465, dated December 29, 1896.

Application filed May 8, 1895. Serial No. 548,603. Term of patent 14 years.

To all whom it may concern:

Be it known that I, FRANK K. HESSE, a citizen of the United States, residing at Boston, in the county of Suffolk, State of Massachusetts, have invented and produced a new and original Design for Toe-Clips for Bicycles and the Like, of which the following is a specification, reference being had to the accompanying drawing, forming part thereof.

- o The figure is a perspective view of a toe-clip, showing my novel design.

The leading feature of my design consists in a toe-clip widened across the toe-bend and divided thereat to form two separated portions, which are turned into opposite angles to approximate the curvature of a toe of a shoe in position in the bend.

Referring to the drawing, the toe-clip consists, essentially, in a shank *a* and a toe or loop portion *b* and the end *c*.

At the toe-bend where the shank and loop portion are joined the width of the clip is considerably increased, as shown, and is di-

vided to form two separated members *a'*, separated by a considerable space *a²*, these 25 members *a'* being turned into opposite angle positions, as shown, to approximate the curvature of an end of a shoe in position in the clip, said angle members forming a sort of a bracket to retain the sole of the shoe against 30 lateral movement.

At the shank-bend, that is, at the bend between the shank and the end *c*, the normally-flattened metal of the clip presents a convex or crowning form, as at *a⁴*. 35

What I claim is—

The design for a toe-clip herein shown and described.

In testimony whereof I have signed my name to this specification in the presence of 40 two subscribing witnesses.

FRANK K. HESSE.
